UNITED STATES PATENT OFFICE

EARL STUMP, OF CHICAGO, ILLINOIS, ASSIGNOR TO ROBERTS AND SCHAEFER COMPANY, OF CHICAGO, ILLINOIS, A CORPORATION OF ILLINOIS

HYDRAULIC CLEANER CONTROL

Application filed December 13, 1929. Serial No. 413,716.

This invention relates to a material cleaning device and particularly to means adapted to prevent clogging of the discharge passage of such a device.

In one form, this invention is applied to a hydro-separator adapted to separate coal from other material. Many of the impurities present with the coal are heavier than the coal and the mechanism to which my invention may be applied embodies means for subjecting the coal and refuse to a powerful upward current of water. The coal is raised and carried off over a partition and the refuse, by reason of its greater weight, passes downwardly and is discharged through an opening. The opening is controlled by means of a gate which may be lowered to close the opening entirely and may be adjusted to vary the size of the opening. It is one of the objects of my invention to provide means for acting upon the gate to prevent clogging of the refuse at the discharge opening which is controlled by the said gate. Other objects appear from time to time in the specification and claims.

The invention is illustrated in the accompanying drawing, which is a fragmentary, vertical cross section, showing a hydro-separator with my gate installed and with parts omitted.

A indicates a chamber into which coal A¹ is delivered by means of a chute A². The chamber A is formed by suitable walls and is generally water tight. A partition A³ is provided with an opening A⁴ at its bottom. A gate A⁵ is provided to control the opening A⁴. It may be moved to close it entirely or to vary the size of the opening. A⁶ is a controlling rod by means of which the gate is raised and lowered. The rod is threaded at its upper end as at A⁷ and is provided with a wheel A⁸. A⁹ is a support for the rod A⁶. A¹⁰ is a screen which forms the bottom of the chamber A.

B is a water chamber located beneath the chamber A and separated from it mainly by the screen A¹⁰. B¹ is a nozzle projecting into the chamber B by means of which a current of water may be discharged into the chamber B. The movement of the current of

water is indicated by arrows, particularly in chambers A and B.

C—C are particles of coal moving upwardly in the current of water after they have been separated from the refuse D which is shown as moving downwardly along the screen A¹⁰ toward the discharge opening A⁴. E is a chute onto which the coal is discharged as it passes from the chamber A over the partition A³. It may be removed and de-watered in any suitable manner.

F is a rotating shaft provided with a cam member F¹ positioned on it and adapted to rotate with it. F² is the cam part formed on the member F¹.

G is a lever supported for movement at G¹ in a member G² which may be mounted on the framework of the hydro-separator or may be supported in any other suitable manner. As indicated in the drawings one end of the lever G contacts the hand wheel A⁸ and the other is periodically depressed by the cam F².

It will be evident that while I have shown in my drawing an operative device, still many changes might be made in the size, shape, arrangement and disposition of parts, without departing from the spirit of my invention. In particular, the mechanism for giving the gate its reciprocatory or vibratory movement might be widely changed and the direction, amount and nature of the movement given to the gate to prevent clogging might be almost infinitely changed without departing from the spirit of my invention.

When in this specification and in the claims the expression "vibratory" or "reciprocatory" movement is used, I mean in general a shaking action; ordinarily a motion of the type shown would be satisfactory and as shown, of course, it is a regular reciprocatory movement. An irregular movement might be used and for the purposes of the invention almost any jarring or shaking movement might be satisfactory.

The use and operation of the invention are as follows:

With the parts in the positions shown, a combined stream of coal and refuse is discharged into the chamber A, which is filled with water. The water is circulated by dis-

charging through the nozzle B¹ and passing over the partition A³. As the stream of coal and refuse passes into this upwardly moving current of water the greater part of the coal follows the upwardly rising current, is separated from the refuse and passes over the partition and is collected by means of the chute E or by any suitable mechanism. At the same time the heavier refuse resists the effect of the upwardly rising current of water, passes downwardly across the screen and is discharged from the chamber A and thereafter is collected and removed in any suitable manner.

It has been found that for any one of many reasons clogging sometimes tends to take place at the point of discharge of the refuse from the chamber A. I have discovered that if the gate which controls the size of the discharge opening is given a slight vibratory movement, the tendency for clogging is greatly reduced. In the form of my invention shown herewith I have, therefore, provided means for reciprocating the gate very slightly in a more or less vertical path. The gate is thus raised and lowered constantly. The amount of the movement is slight, in some cases not more than $\frac{1}{2}$ inch and in some cases even less. The lever action illustrated causes this reciprocatory movement. In apparatuses of this sort it is practically certain that there will be a rotating shaft and it is generally convenient to mount the cam on such a shaft. The lever may then be positioned so as to be periodically depressed by the cam and with each depression of the lever at one end its opposite end is raised and in the form shown herewith the lever thus contacts the hand wheel on the gate shaft and raises it. As soon as the cam has passed out of engagement with the lever, the gate is free to drop and does so, raising the lever at one end while depressing it at the other, and this alternate raising and lowering of the gate will take place as long as the parts are in motion.

I claim:

1. In combination in a hydraulic separator having a stationary separating chamber, means for supplying mixed materials to said chamber and means for forcing a current of water through said chamber, said chamber provided with a discharge for the refuse and a discharge for the cleaned material, a gate member adapted to control the discharge of refuse, axially movable adjustment members for said gate to vary the size of the discharge opening including a handle, and means engaging said handle and operable to impart vibratory movement of said gate.
2. In combination in a hydraulic separator having a separating chamber, means for supplying mixed materials to said chamber and means for forcing a current of water through said chamber, said chamber being provided with a discharge for refuse and a discharge

for clean material, a gate member adapted to control the discharge of refuse, means for adjusting said gate to vary the size of the discharge including a handle, a walking beam having one end engaging said handle, and a cam engaging the opposite end thereof whereby operation of the cam causes vibration of the discharge gate.

Signed at Matoka, county of Mercer, and State of West Virginia, this 15th day of November, 1929.

EARL STUMP.
